UNITED STATES PATENT OFFICE.

SAMUEL STEPHENS, OF SOMERVILLE, MASSACHUSETTS.

PRINTER'S QUOIN.

No. 911,173.

Specification of Letters Patent.

Patented Feb. 2, 1909.

Application filed August 12, 1907. Serial No. 388,153.

To all whom it may concern:

Be it known that I, SAMUEL STEPHENS, a citizen of the United States, residing at Somerville, in the county of Middlesex and State 5 of Massachusetts, have invented an Improvement in Printers' Quoins, of which the following description, in connection with the accompanying drawings, is a specification, like letters on the drawings representing like 10 parts.

This invention relates to quoins for printers' use.

In order that the principles of the invention may be clearly understood, I have in the 15 accompanying drawing disclosed one type or embodiment thereof wherein is represented a preferably metallic quoins adapted to be expanded to meet the varying requirements of practical use.

20 In said drawings: Figure 1 represents a plan view of a quoins embodying my invention, a portion thereof being broken away to show the interior construction; Fig. 2 represents a side elevation thereof, the quoins being 25 represented as non-expanded or compacted; Fig. 3 is a vertical central section of the quoins with the preferred embodiment of means for expanding the same in accordance with my invention, the quoins being represented as non-expanded; Fig. 4 is a similar 30 view of the same construction of parts but representing the quoins as expanded but preserving its rectangular formation; Fig. 5 is an interior plan view of one of the members 35 of the quoins which, for purposes of description, is herein denominated the upper member; Fig. 6 is a similar view of what is herein termed the lower member; Fig. 7 is a view of parts similar in construction to those represented in Figs. 3 and 4, but representing the 40 quoins as expanded into a non-rectangular formation; and Fig. 8 is a perspective view of a form of fulcrum that may be employed in connection with my invention.

45 Referring specifically to the drawing, the quoins typifying the preferred embodiment of the invention is composed of two members 1 and 2, herein respectively termed for convenience of description upper and lower 50 members. Preferably such members are metallic and one of them, and herein the lower, may be provided with a projecting portion or tongue 3 adapted to be received within a preferably correspondingly shaped 55 recess or opening 4 in the other member.

It is highly desirable that a quoins be pro-

vided with means whereby the exterior operative faces of the members may be disposed at such angles as effectively to bind the work in position, and conform if necessary to uneven surfaces, such as may be afforded by bent chases, uneven furniture, out-of-square blocks and the like.

I am aware that it has been attempted to provide a quoins, the faces of which may be disposed out of parallelism. By my invention, however, I am enabled to provide a quoins, the faces of which may effectively be disposed in parallelism or at any desired angle, with great simplicity of construction. 70 In the present embodiment of my invention this is most effectively accomplished by providing compound fulcrum fixed in position and distinct from the members of the quoins, or provided upon one of them. Herein such 75 fulcrum are represented as spreading devices 5 and 6 distinct from the members 2 and 3, being interposed between them in socketed portions 7, 7' and 8, 8'. It will be apparent, however, that within the scope of my invention other forms or constructions of fixed 80 fulcrum may be provided. Herein, each of said devices is provided as shown in Fig. 8 with cam portions 9, 10 and 11, the portions 9 and 11 being adapted to coöperate 85 with the raised faces 12 and 13 in the lower member 2, the intermediate cam portion 10 being adapted to coöperate with the raised face 14, herein provided upon the upper member 1. It is apparent, however, that 90 any suitable expanding means may be employed instead of that shown. It is evident that upon imparting a rotative movement to either or both of the spreading devices 5 and 6 the members 1 and 2 of the quoins are separated from each other to an extent depending upon the degree of rotation of said spreading devices and in opposition to the coil 95 springs 15 herein employed to maintain said member normally compacted. Herein said 100 springs are contained within recessed end portions of said members 1 and 2 and engage ears 16 upon said members. Preferably each of said spreading devices 5 and 6 is provided with means whereby a movement of 105 rotation may be imparted thereto. For such purpose said devices are, in this embodiment of the invention, provided with squared openings 17 to receive a key or the like.

By the use of a plurality of provisions 110 whereby the quoins members may be separated, I provide in effect compound fulcrum,

which herein are represented by devices separate from the members 1 and 2. Inasmuch as in this type of the invention the spreading devices rotate upon fixed axes and 5 are not displaced longitudinally of the quoin in the operation thereof, the quoin may be of minimum length.

In order that the quoin may be carefully adjusted to a predetermined position and 10 furthermore in order that the degree of separation of the members may be readily determined at any time, I have provided means herein consisting of one or more scales 18 preferably disposed near opposite ends of the 15 quoin. If desired, such scales may be provided upon metallic or other strips 19 pinned or otherwise secured to one of the members and overlapping the other, as clearly represented in Fig. 2. If desired, such strip or 20 strips may be provided upon a recessed portion or portions of one of the members, so that the exposed surface of the quoin may be smooth and even.

Having thus described one type or embodiment of my invention, I desire it to be understood that although specific terms are employed, they are used in a generic and descriptive sense and not for purposes of limitation, the scope of the invention being set forth 30 in the following claims.

Claims.

1. A quoin having a pair of opposed, short, rigid members each having a continuous outer face and a pair of bodily fixed, adjustable fulcra interposed between said members and about which said members rock relatively to each other upon adjustment of said fulcra while maintaining their rigid, non-flexed condition, said fulcra being accessible 35 for adjustment at the side of the quoin when in use, said fulcra being independently adjustable, whereby the outer faces of said members may be relatively inclined throughout their entire length at any desired angle.
- 40 2. A quoin having a pair of opposed, short, rigid members, each having a continuous outer face and a pair of fulcra mounted for rotation in the plane of the longitudinal axis

of said quoin, said fulcra being interposed between said members upon opposite sides 50 of the center thereof and accessible for adjustment at the side of the quoin when in use, and about which said members rock relatively to each other upon rotative adjustment of said fulcra, while maintaining their rigid, non-flexed condition, said fulcra being independently adjustable, whereby the outer faces of said members may be relatively inclined throughout their entire length at any desired angle. 55

3. A quoin having a pair of opposed, short, rigid members, each having a continuous outer face and a pair of adjustable fulcra interposed between said members and about which said members rock relatively to each other upon adjustment of said fulcra while maintaining their rigid, non-flexed condition, said fulcra being accessible for adjustment at the side of the quoin when in use, said fulcra being independently adjustable, whereby the outer faces of said members may be relatively inclined throughout their entire length at any desired angle. 60

4. A quoin having a pair of opposed, short, rigid members, each having a continuous outer face and a pair of adjustable fulcra interposed between said members and about which said members rock relatively to each other upon adjustment of said fulcra while maintaining their rigid, non-flexed condition, said fulcra being accessible for adjustment at the side of the quoin when in use, said fulcra being independently adjustable, whereby the outer faces of said members may be relatively inclined throughout their entire length at any desired angle. 70

In testimony whereof, I have signed my name to this specification, in the presence of two subscribing witnesses.

SAMUEL STEPHENS.
